UNITED STATES PATENT OFFICE.

GUSTAF DAVID SUNDSTRAND, OF ROCKFORD, ILLINOIS, ASSIGNOR TO ROCKFORD MILLING MACHINE COMPANY, OF ROCKFORD, ILLINOIS, A CORPORATION OF ILLINOIS.

GEARING.

Application filed January 31, 1919. Serial No. 274,158.

To all whom it may concern:

Be it known that I, GUSTAF DAVID SUNDSTRAND, a citizen of the United States, residing in the city of Rockford and State of Illinois, have invented new and useful Improvements in Gearing, of which the following is a specification.

The invention has reference to gearing for milling machines and the like, and one object thereof is to provide an improved construction and arrangement of the gearing and the controlling devices therefor wherein such devices are arranged in a very compact manner, present a neat and ornamental appearance, and are very convenient for the operator.

Another object of the invention is to provide, in combination with change speed gearing of advantageous construction, improved mechanism for actuating the gearing in either direction.

Another object of the invention is to provide for changing the speed ratio between two shafts through a series of increments all in the same sense, by sliding a set of gears on one of the shafts through a corresponding series of predetermined positions of adjustment.

The objects of the invention thus generally stated, together with other and ancillary advantages, are attained by the preferred construction and arrangement illustrated in the accompanying drawings, forming part hereof, in which Figure 1 is a fragmentary longitudinal sectional view of a portion of a milling machine embodying the features of my invention. Fig. 2 is a transverse vertical section taken on line 2—2 of Fig. 1. Fig. 3 is a fragmentary horizontal section taken on line 3—3 of Fig. 2. Fig. 4 is a fragmentary vertical section taken on line 4—4 of each of Figs. 1 and 3. Fig. 5 is a fragmentary side elevation showing the arrangement of the controlling devices. Fig. 6 is a fragmentary horizontal section taken on line 6—6 of Fig. 2. Fig. 7 is a vertical sectional view taken on line 7—7 of Fig. 1. Fig. 8 is a sectional view taken on line 8—8 of Fig. 1.

The frame of the machine in which the invention is embodied is indicated generally at 1, and 2 indicates a cutter spindle mounted in suitable bearings in the frame and driven, through the medium of gearing to be de-

scribed, from a shaft 3 mounted at the forward end of the frame and having a drive pulley 4 thereon. The spindle 2 thus constitutes the driven shaft, and the shaft 3 the main drive shaft, while 5 indicates a tumbler shaft, which is driven from the drive shaft in a manner to be later set forth, and 6 indicates an intermediate shaft having gearing connections with both the tumbler shaft and the spindle or driven shaft whereby the latter is actuated.

The gearing connections between the driven shaft 2 and the intermediate shaft 6 comprise three gears 7, 8 and 9 of varying sizes on the driven shaft, and three gears 10, 11 and 12 fixed against rotation as well as sliding movement on the intermediate shaft 6. The gear 7 on the driven shaft is loosely mounted thereon and meshes at all times with the gear 10 on the shaft 6; and the gears 8 and 9 are slidably but non-rotatably mounted on the driven shaft 2. The gears 8 and 9 are thus movable into mesh with the gears 11 and 12 respectively on the shaft 6. In order that the driven shaft 2 may be actuated through the medium of the gears 7 and 10, the gear 7 is arranged to be locked against rotation relative to the shaft 2 by the gear 8. For this purpose the adjacent faces of the gears 7 and 8 are provided with suitable clutch devices which may comprise a series of pins 13 (Fig. 1), suitably mounted in the gear 7, and a corresponding number of openings 14 (Fig. 8) in the gear 8 for receiving the pins when the gear 8 is slid into engagement with the gear 7. When in this position, the gears 8 and 9 on the shaft 2 are out of mesh with the gears 11 and 12 on the shaft 6.

The tumbler shaft 5, which is constantly driven in one direction or the other in a manner to be later set forth, is journaled at its opposite ends in the walls of a tumbler 15. This tumbler is in the form of a casing pivotally mounted at its rear end on a shaft 16 (Fig. 4), and fixed on said tumbler shaft 5 at spaced intervals are three gears 17, 18 and 19 movable by swinging the tumbler, into mesh with two contiguous gears 20 and 21 slidably but non-rotatably mounted on the shaft 6. By spacing the tumbler gears 17, 18 and 19 apart sufficient to receive one of the gears 20 or 21 while the other meshes with one of said tumbler gears, it is possible,

upon sliding the gears 20 and 21 on the shaft 6 and swinging the tumbler to move any one of the tumbler gears into mesh with either of said gears 20 and 21. It will be seen that by the construction set forth, the tumbler gears may be moved into mesh with each of the gears 20 and 21, whereby six variations in speed are obtainable through these connections, and since three variations in speed are obtainable through the connections between the shafts 6 and 2, an aggregate of eighteen variations in speed between the tumbler shaft 5 and the driven shaft 2 is obtainable.

15 I prefer to make the pitch diameter-ratio of the gears 20 and 21 nearer unity than the ratio between the gears 18 and 17 and 19 and 18. When this is done the six different positions of the sliding gears will correspond to six different speed ratios, each speed ratio in the series being greater than the preceding one. For instance, in the design shown, gears 17 and 20 give the slowest speed for shaft 6. The next position of the 20 sliding gears will use gears 21 and 17, increasing the speed of shaft 6 by the ratio between gears 20 and 21. The next position will use gears 20 and 18 and if the ratio of gears 18 and 17 is greater than the ratio of gears 20 and 21, gears 18 and 20 will drive shaft 6 at a higher speed than gears 17 and 21. It will thus be seen that an uninterrupted series of positive increments in the speed of shaft 6 is obtainable by moving the 25 sliding gears from one position to the next throughout the series of positions.

Referring now to Figs. 4 and 5, the gear-controlling means comprises two rotary devices 22 and 23 and one horizontally movable device 24. These devices are all mounted on a plate 1^a suitably secured to the forward wall of the frame 1, with the horizontally movable device 24 disposed between the rotary devices 22 and 23; and said devices 22, 23 and 24 are operatively associated with the gearing so as to control, respectively, the positions of the gears 8 and 9 on the shaft 2, the tumbler gears 17, 18 and 19 through the tumbler 15, and the gears 20 and 21 on the shaft 6.

The rotary controlling device 22 may comprise a crank 25 fixed on the outer end of a crank rod 26, which is journaled in the controller plate 1^a and has fixed on its inner end a pinion 27. A rack bar 28, slidably mounted on the inner side of said plate 1^a and with which said pinion meshes, carries a member 29, the inner end of which is grooved (Fig. 6) to receive a collar 30 formed on a sleeve 31 on the driven shaft 2, said sleeve being rigid with the gears 8 and 9 on said shaft.

The rotary device 23 comprises a crank 32 fixed on the outer end of a crank rod 33 carried by the controller plate and having

a pinion 34 on its inner end. This pinion is located at one side of the forward end of the tumbler 15 and the tumbler is provided with a gear segment or rack 35 with which the pinion is adapted to mesh.

The horizontally movable device 24, which is adapted to shift the gears 20 and 21 on the shaft 6 comprises a pin 36 entered through a slotted plate 37 secured to the controller plate 1^a. Said pin has a handle 38 on its outer end and a member 39 on its inner end adapted to slidably engage with the opposite sides of the gear 20 on the shaft 6. At the opposite edges of the slot in the plate 37 a series of six recesses 40 are provided corresponding to the positions in which the gears 20 and 21 are to be moved to obtain the six variations in speed between the shaft 6 and the tumbler shaft 5. Into these recesses the inner end of the handle 38 is adapted to be forced by a spring 41 (Fig. 4) whereby the member 39 may be releasably fixed in the desired position of horizontal adjustment. Similarly, in order that the member 29 which is actuated by the crank 25, and the tumbler 15, which is swung by the crank 32, may be releasably held in their several positions, the handles of said cranks are each provided with a spring-pressed detent 42 adapted to engage with recesses or sockets 43 or 43^a arranged at properly spaced intervals in the controller plate.

The means for driving the tumbler shaft 5 will now be described, reference being made particularly to Figs. 1, 2, 3, and 7. As shown in Figs. 3 and 7, the shaft 16 upon which the tumbler 15 is pivotally mounted is suitably journaled in the forward portion of the frame 1 parallel to the main drive shaft 3 but slightly above and at one side thereof, the tumbler 15 being mounted on the inner end of the shaft 16.

The drive shaft has fixed thereon a gear 44 which meshes at all times with two gears 45 and 46. The gears 45 and 47 are fixed on a shaft 45^a mounted directly below the shaft 16. The gear 47 is adapted to mesh with a gear 48 slidably but non-rotatably mounted on the shaft 16, so that when the gears 47 and 48 are in mesh the shaft 16 will be actuated. The shaft 16 in turn has fixed thereon a gear 49 meshing at all times with the tumbler gear 19. Thus the tumbler gears may be driven from the drive shaft in one direction through the gears 44, 45, 47, 48 and 49 from the main drive shaft. In order that said tumbler gears may, when desired, be driven in the opposite direction from the drive shaft, the gear 48 on the shaft 16 is moved out of mesh with the gear 47 and into interlocking engagement with the gear 46. This latter gear is loosely mounted on the shaft 16 and meshes at all times with the gear 44 on the main drive

shaft, the gear 48 serving to lock said gear 46 against rotation on the shaft 16 so that the tumbler gears may be driven through the gears 44, 46 and 49. In order that the gears 46 and 48 may interlock they may be provided with clutch teeth 50 and 51 (Fig. 3), and for the purpose of shifting the gear 48 a rotary device is provided comprising a crank rod 52 suitably mounted in the frame 10 1 and having a crank 53 on its inner end and a knurled head 54 on its outer end. The gear 48 has rigid therewith a hub 55 which is provided with a groove 56 in which the inner end of the crank pin of the crank 53 is adapted to operate to effect a shifting of the gear 48 when the knurled head 54 is rotated.

It will be seen that I have provided change speed gearing which is capable of transmitting power from a drive shaft to a driven shaft at a great variety of speeds and in either direction, and that the gearing is so combined with the shifting or controlling devices as to enable an advantageous arrangement of the latter. By mounting two gears 20 on the shaft 6 so as to be shiftable with reference to the tumbler gears, the necessity for sliding the tumbler, as is the case in some prior devices, is eliminated. Hence it is possible to greatly simplify and strengthen 25 the tumbler and the means for swinging it. Moreover the arrangement of the shaft 6 between the driven shaft 2 and the tumbler enables the advantageous arrangement 30 of the gear-shifting devices 22, 23, and 24 above set forth.

It will also be noted that in the construction and arrangement of the gearing set forth, the tumbler 15 is made to support both ends of the tumbler shaft 5, it being 40 evident that inasmuch as the tumbler is not slid endwise there is no danger of the bearings for the shaft interfering with any of the gear-shifting operations.

In Fig. 1, the drive shaft 3 is shown as 45 provided on its inner end with a gear 57 meshing with a gear 58 to actuate a gear 59. These gears are a part of the feed mechanism forming no part of this invention.

While I have described one embodiment 50 of my invention as illustrated in the drawings, it is to be understood that I do not desire to be limited to this particular embodiment of the principles and features disclosed throughout the description. My invention broadly considered and expressed in 55 the appended claims is to be limited only by the prior art.

I claim as my invention:

1. The combination of a pair of shafts, 60 means adapted to connect said shafts so that one shaft may be driven from the other at a variety of speeds, a pivotally mounted tumbler having a shaft with a plurality of gears thereon of different sizes, a plurality of 65 gears on one of said pair of shafts shiftable

into and out of position to be operatively engaged by the gears in said tumbler, means for driving the tumbler shaft, means for sliding said shiftable gears, and means for swinging said tumbler. 70

2. The combination of a shaft having a plurality of gears shiftable but non-rotatably mounted thereon, a pivotally mounted tumbler having a shaft with a plurality of gears fixed thereon, means for driving the tumbler shaft, and means for swinging said tumbler to carry its gears into mesh with the first mentioned gears, said tumbler gears being spaced apart so that when one of the first mentioned gears is brought into mesh with one of the tumbler gears the remainder of the first mentioned gears may enter the space between two of the tumbler gears. 75 80

3. In a machine of the class referred to, a drive shaft, a driven shaft, and means adapted to connect said two shafts whereby the one shaft may be driven by the other at a plurality of different speeds, said means including a shaft adapted to be connected with the drive shaft for rotation thereby, a tumbler 85 pivotally mounted on the last mentioned shaft and having a plurality of gears mounted therein, and a shaft between said tumbler and the driven shaft operatively connected with the driven shaft and having a plurality 90 of gears thereon shiftable into and out of position for engagement by each of the tumbler gears. 95

4. In a machine of the class referred to, a drive shaft, a driven shaft, and means 100 adapted to connect said two shafts whereby one shaft may be driven by the other in either direction at a plurality of different speeds, said means including a third shaft having a gear loosely mounted thereon, a 105 gear on the drive shaft meshing at all times with said loose gear, a tumbler on said third shaft having a shaft therein adapted to be operatively connected with the driven shaft, a fourth shaft selectively connected at various speed ratios with the drive shaft and having a gear fixed thereon, and a gear on 110 said third shaft adapted to mesh with the gear on the fourth shaft and movable into interlocking engagement with the loose gear 115 on the third shaft to hold it against rotation thereon.

5. The combination of a pair of shafts, 120 means adapted to form various operative connections between said shafts whereby one shaft may be driven from the other at a plurality of different speeds, a third shaft, a tumbler pivotally mounted on said third shaft and having a shaft therein operatively connected with said third shaft, means for driving said third shaft in either direction, and means independent of said means for connecting said pair of shafts, and including a plurality of gears on said tumbler shaft 125 adapted to operatively connect said tumbler 130

- shaft to drive one of said pair of shafts at a variety of speeds.
6. In a machine of the class referred to, a shaft to be driven, a tumbler pivotally mounted at one end and having a shaft therein, an intermediate shaft, gears on each of said shafts movable into various positions of adjustment to effect a variation in speed of the driven shaft, a rotary device for sliding the gears on the driven shaft, a rotary device for swinging the tumbler and the gears therein, and a device disposed between the rotary devices and movable substantially rectilinearly to slide the gears on the intermediate shaft.
7. In a machine of the class referred to, a pair of shafts and an intermediate shaft, gears on each of said shafts movable into various positions of adjustment to obtain a plurality of different speeds, means for moving said gears comprising a pair of devices for the gears on said pair of shafts each including a hand crank disposed one above the other, and a third device for the gears on the said intermediate shaft including a pin movable substantially horizontally and disposed between the hand cranks of the other two devices.
8. In a machine of the class referred to, a pair of shafts and an intermediate shaft, gears on each of said shafts movable into various positions of adjustment to effect a variation in speed of one of said shafts, rotary devices for moving the gears on said pair of shafts, and a device for moving the gears on said intermediate shaft disposed between said rotary devices and movable in a path substantially at right angles to a line connecting the axes of said rotary devices.
9. The combination of a shaft having a plurality of gears slidably but non-rotatably mounted thereon, a tumbler pivotally but non-slidably mounted on an axis parallel to said shaft, a shaft mounted in the tumbler and having a plurality of gears fixed thereon, and devices for sliding the first mentioned gears and swinging said tumbler whereby any one of the tumbler gears may be brought into mesh with any one of the first mentioned gears.
10. In a variable speed power transmission, a driven shaft, an intermediate shaft parallel to said driven shaft, a tumbler shaft extending parallel to a portion of the length of said intermediate shaft only, slidable gears on the portion of said intermediate shaft adjacent said tumbler shaft adapted to be driven from said tumbler, and fixed gears on the other portion of said intermediate shaft adapted to drive said driven shaft.
11. In a variable speed transmission, a pair of shafts, a plurality of fixed gears and a plurality of slidable gears on the first shaft, a plurality of driven gears on the second shaft adapted for selective engage-

ment with the fixed gears of the first shaft, and other coaxial gears of various sizes adapted to be moved into selective engagement with said slidable gears of the first shaft.

12. In a device for transmitting power at a plurality of speed ratios, a rotary control element adapted to shift gears axially into mesh with other gears, a second slideable control element adapted to shift other gears axially, a third rotary control element adapted to move gears into mesh without sliding them, the axes of said three control elements being parallel, and power-transmitting mechanism between said first and third control elements and the gears controlled thereby including mechanism for multiplying the manual force supplied.

13. In a variable speed mechanism, a speed-setting dial, comprising three control elements adjustable in planes parallel to the dial, the first control element having rotary adjustability and having means adapted to shift gears axially into mesh with other gears, the second control element having rotary adjustability and being provided with rack and pinion means whereby easily to swing tumbler gears into mesh with other gears, and the third control element having linear adjustability substantially at right angles to the line of centers of the first and second control elements and having means adapted to shift axially the gears which mesh with the tumbler gears, the first control element acting independently of the other control elements.

14. In a variable speed power transmission, a shaft, a pair of gears of different diameters splined on said shaft, a plurality of gears of different diameters separated by spaces not less than the width of the larger splined gear, means for sliding said splined gears, and means for swinging said spaced gears into mesh with said splined gears.

15. In a variable speed power transmission, a tumbler a shaft pivoted in said tumbler carrying a plurality of gears, a shaft pivotally supporting said tumbler, a gear on said last mentioned shaft continually meshing with one of said tumbler gears, another gear splined on said last mentioned shaft, and a third gear loose on said last mentioned shaft, means for driving said splined and loose gears in opposite directions, said splined gear and said loose gear having cooperating clutch elements, and means for moving said splined gear out of engagement with its driving means and into engagement with said loose gear.

16. In a power transmission, a drive shaft, continuously rotating in one direction, a driven shaft and a countershaft, said drive shaft having a gear meshing with a gear loose on the driven shaft and with a gear rigid on the countershaft, said counter-

shaft having a gear meshing with the slideable gear on the driven shaft, said slideable gear and loose gear having cooperating clutch elements, whereby the slideable gear 5 engages the loose gear when out of mesh with the second gear of the countershaft.

17. A variable speed power transmission, comprising three sets of rotary elements, control means for moving the first 10 set of elements out of operative engagement with the second set, control means for positioning the second set of elements to receive the first set in engagement for power transmission at a plurality of different 15 speed ratios, and control means for positioning the third set to receive power from the second set at a plurality of different speed ratios, the control means for said first and third sets including mechanism for increasing 20 the manual force applied.

18. A variable speed power transmission, having, in combination, three sets of rotary elements, means for withdrawing the first set of elements from operative engagement 25 with the second set, means for positioning idle elements in said second set to receive elements of said first set for transmitting power at a relatively large number of various speed ratios, and means for positioning 30 elements of the third set to receive power from elements of the second set at a relatively small number of various speed ratios, said means for withdrawing the first set of elements operating independently of the 35 position of the elements of the second set.

19. A variable speed power transmission having, in combination, three sets of rotary elements, the intermediate set including slideable elements adapted to receive power 40 from the first set, and the third set including slideable elements adapted to receive power from the said intermediate set, means for withdrawing the first set of elements from operative engagement with the slideable elements of the second set, means including mechanism for increasing the manual force applied for sliding the slideable elements of the third set, and means for 45 sliding the slideable elements of the second set.

20. A variable speed power transmission having, in combination, three pairs of four parallel shafts, one being a tumbler pair comprising a tumbler shaft and a pivot 50 shaft and control means for swinging the tumbler shaft about the pivot shaft, each pair comprising a driving shaft and a driven shaft, the driven shaft of each pair being the driving shaft of the next pair, the 55 tumbler pair having a rigid driving gear and a rigid driven gear, the remaining pairs having spaced driving gears rigid to the shaft and contiguous driven gears slideable on the shaft, and having control means for 60 sliding said driven gears, whereby selective 65

engagement of gears within the pairs is obtained.

21. In a machine of the class referred to, an intermediate shaft and a final shaft, fixed gears on said said intermediate shaft, and 70 means carried by said final shaft for connecting it to said intermediate shaft at any one of a plurality of different speed ratios, gears on said intermediate shaft slideable into any one of a series of predetermined 75 positions, and adjustable gears for driving said slideable gears at a predetermined speed in each position of adjustment, the speeds corresponding to the different positions of adjustment increasing uninterruptedly 80 throughout the series.

22. In a variable speed transmission, a pair of shafts comprising a driving shaft and a driven shaft, the driving shaft having a plurality of spaced gears fixed to its shaft, 85 a driven shaft having contiguous driven gears slideable on the shaft, and means for producing the meshing of any one driven gear with any one driving gear, the pitch diameters of said driven gears having a 90 ratio nearer unity than that of the pitch diameters of any two adjacent driving gears.

23. In a variable speed transmission, a shaft, two contiguous gears of different diameters splined on said shaft, a plurality of gears of different diameters, each of said last mentioned gears spaced from each adjacent gear by a space not less than the width of the larger splined gear, the pitch 95 diameters of said spaced gears increasing uninterruptedly throughout the series, the ratio between the pitch diameters of the splined gears differing from unity by an amount less than the ratio between the 100 pitch diameters of any two adjacent spaced gears, and means for producing the meshing of any one of said splined gears with any one of said spaced gears, whereby said 105 splined gears may in their various positions 110 of adjustment be driven at a series of different speeds increasing uninterruptedly throughout the series.

24. A variable speed power transmission having, in combination, a driving shaft and a driven shaft, a set of gears on each shaft, means for moving one shaft toward and away from the other to bring the gears into and out of mesh, and means for sliding one set of gears to associate any gear in the slideable set with any gear in the other set, the pitch diameters of the gears being such that an uninterrupted series of speed increments in the same sense, corresponding to the linear series of positions of adjustment of 125 the slideable gears, is provided for the driven shaft.

25. In a variable speed transmission, a shaft, gears of different diameters splined on said shaft, others gears of different diam- 130

eters the ratio between the pitch diameters of adjacent splined gears differing from unity by an amount less than the ratio between the pitch diameters of any two adjacent other gears, and means for producing the meshing of any one of said splined gears with any one of said other gears.

26. In a variable speed transmission, a pair of shafts, two gears of different diameters splined on the first shaft, a plurality of gears of different diameters, on the second shaft the pitch diameters of said last mentioned gears increasing uninterruptedly throughout the series, the ratio between the

pitch diameters of the splined gears differing from unity by an amount less than the ratio between the pitch diameters of any two adjacent other gears, and means for producing the meshing of one of said splined gears with any one of said other gears, whereby said splined gears may in their various positions of adjustment be driven at a series of different speeds increasing uninterruptedly throughout the series:

In testimony whereof, I have hereunto set my hand:

GUSTAF DAVID SUNDSTRAND.

Certificate of Correction.

It is hereby certified that in Letters Patent No. 1,473,166, granted November 6, 1923, upon the application of Gustav David Sundstrand, of Rockford, Illinois, for an improvement in "Gearing," errors appear in the printed specification requiring correction as follows: Page 3, line 94, claim 3, for the word "operatively" read *selectively*, and after the word "connected" insert the words *at various speed ratios*; same page, line 110, claim 4, for the word "selectively" read *operatively*; same page and claim, lines 110 and 111, strike out the words "at various speed ratios"; and that the said Letters Patent should be read with these corrections therein that the same may conform to the record of the case in the Patent Office.

Signed and sealed this 18th day of December, A. D., 1923.

[**SEAL.**]

KARL FENNING,
Acting Commissioner of Patents.
